United States Patent Office.

JOHN MOHN, OF DETROIT, MICHIGAN.

Letters Patent No. 66,242, dated July 2, 1867.

IMPROVED RAILWAY CHAIR.

The Schedule referred to in these Letters Patent and making part of the same.

TO WHOM IT MAY CONCERN:

Be it known that I, JOHN MOHN, of Detroit, in the county of Wayne, and State of Michigan, have invented an Improved Railroad Joint; and I do hereby declare the following to be a full, clear, and exact description thereof, reference being had to the accompanying drawings, making part of this specification, in which—

Figure 1 is a top view of my improved rail joint.

Figure 2 is a transverse section, taken in the vertical planes indicated by the course of the red lines $z z$, fig. 1.

Figure 3 is a perspective view showing the chair spiked down upon a cross-tie ready for receiving the ends of two sections of rail.

Figure 4 is a perspective view of an auxiliary supporting and holding-down plate for the ends of the rail sections.

Similar letters of reference indicate corresponding parts in the several figures.

This invention relates to an improved mode of protecting railroad sections at their joints, and preventing the ends of the sections of rail from springing from their seats, or being crushed or battered down by the concussions incident to the passing and re-passing of trains over them.

The nature of my invention consists in so constructing a railroad rail chair that it shall afford a solid support for the ends of the rail sections, prevent said ends from lateral displacement, afford a means for holding the rail ends down firmly in place, form a portion of the head of the rails at the ends thereof, and also receive a supporting plate which breaks joints with the rail joint; all as will be hereinafter described.

The invention further consists in adapting one of the side supporting plates for the rail joint to serve also as a capping-plate for the spikes which hold the rail chair down to its cross-tie, and thereby prevent the said spikes from working loose, as will be hereinafter described.

The invention further consists in constructing upon the rail chair an elevated portion, which, when recessed into the ends of the rail sections, shall break joints therewith and serve as a means for supporting and receiving the shocks of the rolling load, and preventing the crushing or laminating of the rail at its joints, as will be herein-after described.

To enable others skilled in the art to understand my invention, I will describe its construction and operation.

In the accompanying drawings, A A represent the ends of two rail sections which are supported, protected, and held down upon the cross-tie C by my improved method. A rectangular piece is cut out of each end of each rail section by making a vertical longitudinal cut for a short distance into the centre of the end of each rail, and then removing the piece by a transverse cut, so as to leave a rectangular recess $b' b'$, when the ends of the two sections are brought together, as shown in fig. 1. Each end of each rail section should have a piece cut out of it, as above shown, so that when the sections are laid down upon the cross-ties the recesses at their ends will be on the inner sides of the rails. B represents the rail chair, into a groove, j, in which the ends of the rail sections fit, so that the vertical longitudinal faces b' of these sections shall abut snugly against the corresponding face b of an elevation, a , of the chair B. It is not designed to have the ends of the rail sections to fit tightly between the elevations a and K on both sides of the longitudinal groove, but to employ a separate plate, c, with a head, c' , formed on it for clamping and holding the joint firmly against lateral motion. The base plate of the chair B is extended out laterally from the outside of the rail joint, and its edge terminates in a raised lip, a' , the inner edge of which is or should be parallel to the faces of the elevation a . Between this lip a' and the outer edge of the supporting plate c a wedge-key, f, is driven, as shown in figs. 1 and 2, for the purpose of forcibly pressing said plate c against the sides of the rail sections, and thus clamping them firmly. To prevent this key f from becoming loose the set-screw g may be used. Plate c is designed to serve as a means for holding the ends of the rail sections A A down firmly upon the base of the chair B, for which purpose that end of this plate which abuts against the rails is made to conform to the side thereof, as shown in figs. 2 and 4. For holding the plate c down in place I use screw-bolts e e, which pass through oblong holes d d made through this plate and screw into the chair base. The chair B is secured down upon the cross-tie C by means of five spikes h h, i i i, the latter three of which pass through the flat portion k of the chair base, and have their heads countersunk therein, so as to be flush with its surface, as shown in fig. 3, so that when the plate c is applied these spikes will be covered and prevented from drawing out or working loose.

It will be seen from the above description that the elevated portion *a*, which is constructed upon the chair base, fills up the recess left by the removal of portions of the rail sections, and forms a splice for the joint, and also a portion of the rail table. In practice this elevation *a* will be faced with steel, so as to render it more durable and less liable to be crushed. I am aware that it is not new to splice rail sections at their joints, by cutting out portions of such sections and inserting plates which break joints with the rail joints. Such plates require to be secured to the rails by transverse bolts, which are constantly working loose. By my invention the rails are made much stronger and more durable at the joints than at any other point, by transferring the weight and shocks of the rolling load from the rails to the solid chair-pieces *a* at every joint.

What I claim as new, and desire to secure by Letters Patent, is—

1. A railroad chair which is constructed with a solid portion, *a*, a slotted base, *j*, an elevated table, *K*, and an abutting lip, *a'*, adapted for receiving the notched rail-sections *A A*, a supporting and covering plate, *c c'*, and a key, *f*, substantially as described.

2. The mode herein described of securing the chair by means of the spikes *i i* for the purpose set forth.
